FASTENING INSERTING MACHINE

Fred N. La Chapelle, Beverly, Mass., assignor to
 United Shoe Machinery Corporation, Paterson,
 N. J., a corporation of New Jersey

Application December 14, 1934, Serial No. 757,504

25 Claims. (Cl. 1—20)

This invention relates to fastening inserting machines and is illustrated herein as embodied in a machine particularly adapted to insert fibre staples in the manufacture of boots and shoes.

5 The fastening together of shoe parts by means of fibre staples of the type disclosed in United States Letters Patent No. 1,957,216, granted May 1, 1934, on an application filed in my name, has proved to be so successful that it has become desirable to develop fastening inserting machines 10 particularly adapted to the insertion of staples of this character. It is, accordingly, an object of the present invention to provide a simple, effective and reliable fastening inserting machine 15 of a character well adapted to be used for the insertion of fibre staples in the manufacture of boots and shoes.

While the machine herein disclosed as embodying the present invention is by no means limited in its utility to the insertion of fibre staples of the type disclosed in said Letters Patent No. 1,957,216, it has been developed with a view particularly to the insertion of such staples and more specifically to the performance of such operations as, for example, securing soles of 25 stitchdown shoes to their uppers.

When inserting staples of the type referred to it has been found necessary to form holes in the work through which the legs of the staples are driven. In lasting stitchdown shoes, for example, such holes extend through the upper and through the sole member. Under some conditions of operation the staples may inadvertently be pulled out of the work thereby permitting the upper to become loosened. Under other conditions the staples hold satisfactorily and are not pulled out of the work even when substantial force is applied thereto. However, in order to insure that under all conditions of operation the 40 staples will not be pulled out of the work, it is desirable to provide means for compressing the work to increase the holding power of the staples and for deflecting or turning the ends of the legs of the staples toward the surface of the work after 45 the staples have been inserted therein. The illustrated machine, therefore, in accordance with one feature of the invention, is provided with a pair of fingers constructed and arranged to compress the work and to engage the ends of the legs 50 of a staple after the staple has been inserted in the work to turn the ends of the legs toward the surface of the work. In the preferred embodiment of the invention shown in the accompanying drawings, the machine is provided with 55 a pair of awls constructed and arranged to form

staple receiving holes in a work piece, a driver for inserting staples in the holes, a work support arranged to clamp the work during the hole forming and staple inserting operations, and a pair of fingers mounted in the support and constructed and arranged to move toward the work to compress the work between the staple legs and to engage the ends of the staple legs to turn said ends toward the work and away from each other after the staple inserting operation has been completed. In the illustrated machine the awls and drivers reciprocate in passages formed in a throat member, these passages being arranged at an angle to each other and intersecting each other at the lower end of the throat, while the fingers are so arranged that they compress the work between the staple legs thus forcing the work against the staple legs with the result that the staples hold the work more securely.

In order to insure that the parts of the work piece will not be moved relatively to each other or to the fastening inserting means after the fastening receiving holes have been formed, it has been found desirable to provide an improved work support arranged to clamp the work against the throat of the machine during the hole forming, fastening inserting, and clenching operations. To this end a feature of the invention consists of mechanism in a fastening inserting machine comprising a toggle having a link constructed and arranged to engage a projection on a work support after the work support has been moved manually toward work clamping position. In the illustrated embodiment of the invention a member is secured to the work support and a pair of links forming a toggle arranged to move the support to clamp the work during the staple inserting operation. One of these links, as illustrated, is pivoted to the frame of the machine and the other link is arranged to engage the member secured to the support after the support has been moved toward work clamping position. The toggle is straightened by power means arranged to apply a predetermined clamping pressure to the work during the fastening inserting operation.

With the above and other objects and features in view the invention will now be described with respect to the accompanying drawings which illustrate a preferred embodiment of the invention and pointed out in the accompanying claims.

In the drawings,

Fig. 10 is a detail view of the lower portion of 20 the throat showing the staple in position to be inserted in the work.

The invention is illustrated herein as embodied in a machine of the type disclosed in United States Letters Patent No. 1,016,930, granted Feb. 25, 1912, on an application filed in the name of William H. Borden, with the wire feeding mechanism modified, if desired, as illustrated in United States Letters Patent No. 1,388,846, granted August 30, 1931, on an application filed in the name of Matthias Brock. The staple inserting mechanism is mounted in a head 12 (Fig. 1) supported on a column 14 and comprises a driver bar 16 carrying a driver 18 actuated in its driving stroke by a spring operated arm 20 (Fig. 4) ful- 30 crumed at 22 upon a bracket 24 carried by the head 12. The staple inserting mechanism, as illustrated, is substantially the same as the mechanism disclosed in said Letters Patent to Borden to which reference may be had for a detailed description of the parts which it is not considered 40 necessary to describe herein.

The illustrated machine is provided with mechanism for forming fastening receiving holes in a work piece into which staples are driven. A bracket 26 (Figs. 1 and 2) is secured to the head 45 12 by screws 28, 30. The bracket 26 is provided with a channel 32 which forms a guideway for an awl bar 34. A pair of awls 36 are secured to the lower end of the awl bar 34 by means of a clamping screw 38. The channel or guideway 50 32 is so located that the awl bar 34 moves at a slight angle to the path of movement of the driver bar 16 and, as illustrated, this angle is approximately nine degrees. The awls 36 are arranged to reciprocate in holes or guiding pas- 55 sages 40 (Figs. 2 and 8) formed in a stationary throat or abutment 42. The driver 18 reciprocates in a passage 44 also formed in the throat 42. As shown in Fig. 2 the passage 44 is substantially vertical and the holes 40 are arranged at an angle 60 thereto and intersect the passage 44 at the extreme lower end of the throat. The ends of the holes formed in the work by the awls 36 are in the line of drive of the legs of the staples which are moved down the passage 44 and into the work 65 by the driver 18, as will later be described.

The awl bar 34 is provided with an enlarged portion 46 (Fig. 2) to which is secured a headed stud 48 carrying a roll 50. A lever 52 made fast to a shaft 54 (Fig. 3) is provided with a forked 70 end which embraces the roll 50. The shaft 54 is mounted in suitable bearings in a bracket 56 secured to the head 12 of the machine by set screws 58 and studs 62. A collar 64 which is arranged to receive one end of a torsion spring 66 is made 75 fast to the shaft 54. The other end of the spring

66 is secured to a member 68 which is rotatably mounted on one end of the shaft 54. The spring 66 is wound up by rotating the member 68, tension on the spring tending to move the lever 52 in a counterclockwise direction, as viewed in Fig. 4. In order to maintain the tension on the spring 66, a pin 70 which extends through holes formed in the member 68 and the bracket 56 locks the member 68 to the bracket. A lever 74 (Figs. 3 and 5) secured to the other end of the shaft 54 is rotated in a clockwise direction by a lifting cam 72, best shown in Fig. 5. When the cam 72 is rotated the awl bar 34, through the connections above described, is moved upwardly until the end of the lever 74 drops off of the high part 75 of the cam 72. The awl bar 34 is then thrust downwardly by the spring 66, thereby causing the awls 36 to penetrate the work to form a pair of holes for the reception of the legs of a staple 73. Downward movement of the awl bar 34 is limited by an adjustable stop member 76 provided with leather or fibre washers 77 which engage a surface formed on the upper end of the bracket 26. After the fastening receiving holes have been formed the awl bar 34 is returned to the position shown in Fig. 3 by the cam 72.

In order to hold a work piece, for example, a shoe having an upper 78 and a sole member 79 (Fig. 3) mounted on a last 80 in fastening receiving position against the lower end of the nozzle or abutment 42, a work support 82 is provided which is arranged to clamp the work against the abutment 42. Referring now to Fig. 1 it will be noted that the machine is provided with a treadle 84 which is pivoted to the base of the machine. An upwardly extending link 86 is connected to the treadle 84 and to one arm of a lever 88. The other arm of the lever 88 engages the lower end of a work supporting column 90 to the upper end of which is secured the work supporting member 82. The work support 82 is adjustably secured to the upper end of the work supporting column 90 by a block 91 which is provided at its upper face with a dove-tail slot into which fits a dovetail 93 (Fig. 4) forming part of the work support 82. The lower end of the block 91 is provided with a dove tail 95 which fits into a slot formed in the upper end of the column 90. The work support 82 is positioned in a predetermined position relatively to the lower end of the throat 42 and locked in position by means of a pair of clamping screws 97. When the treadle 84 is depressed by the operator, the work supporting member 82 is moved upwardly toward the throat 42 to clamp the work. The machine is also provided with a treadle 92 (Fig. 1) fulcrumed to the base of the machine and provided with an upwardly extending rod 94 which is connected to a suitable clutch mechanism. When the treadle 92 is depressed the clutch will be tripped and the machine started into operation. The mechanism above referred to is described in detail in United States Letters Patent No. 1,291,754, granted January 21, 1919, on an application filed in the name of Matthias Brock.

In order to insure that the work will be firmly clamped during the hole forming and fastening inserting operation it has been found necessary to provide means for automatically moving the work support 82 into position after such movement has been initiated by depression of the manually operated treadle 84. The work supporting column 90 is mounted in bearings formed in a forwardly extending bracket 96 (Fig. 1) secured by suitable studs to the column of the

machine. The work supporting post or column 90 is provided with a notched collar 98 which is secured to the post 90 by a pin 102. Mounted in the lower portion of the bracket 96 is a link 104 which is pivoted to the bracket by a pin 106. The other end of the link 104 is pivotally secured to a link 108 by a pin 110; the links 104 and 108 forming a toggle which when straightened operates to move the support 82 as hereinafter described. A third link 112 is also pivotally connected to the pin 110 and carries a spring pressed plunger 114 which bears against the link 108 normally to maintain the link 108 in the position shown in Fig. 1. The other end of the link 112 is secured by a shaft 116 to arms 118 (Figs. 1 and 5) of bell crank levers 120 pivotally secured to the bracket 96 by a shaft 122. The other arm of each bell crank lever 120 is pivotally connected to a link 124. An adjustable collar 126 surrounds the lower portion of the link 124 and the lower end of a spring 128 surrounding the link 124 bears against the collar 126. The upper end of the spring 128 bears against a collar 130 formed on the end of an arm 130 of a bell crank lever 132. The other arm of the bell crank lever 132 carries a cam roll (not shown) which fits into a cam groove 134 formed in a cam 135. The upper end of the rod 124 passes through the column 130 and is provided with a threaded portion. A nut 136 is threaded on the rod 124 and by turning the nut 136 tension of the spring 128 may be varied, as desired, to increase or decrease the clamping pressure on the work. By this means a yieldable connection between the bell crank lever 132 and the bell crank lever 120 is provided.

When the machine is put in operation and the work support 82 has been moved upwardly by depression of the treadle 84 the rod 124 will be moved downwardly swinging the bell crank lever 40 arms 118 in a counterclockwise direction, thereby swinging the link 104 and the link 108 toward the work supporting post 90. The notch 99 formed in the collar 98 is so positioned relatively to the upper end of the link 108 that, unless the work supporting post 90 has been moved upwardly a predetermined distance by the manually operated treadle 84, the end of the link 108 will not engage the notch 99 but will move past the collar 98 without moving the work support 82. If, on the other hand, the work support 82 has been moved upwardly by depression of the treadle 84 to clamp the work prior to the fastening inserting operation the end of the link 108 will engage the notch 99 in the collar 98 and will clamp the work against the throat 42 with a predetermined pressure. The end of the link 108 engages the notch 99 formed in the collar 98 and as the two links 104, 108 straighten the work support 82 is raised until the work is securely clamped against the throat 42. The spring connection between the bell crank lever 132 and the rod 124 will yield to compensate for variations in the thickness of the work. After the staples have been inserted in the work, the bell crank lever 120 will be moved in a clockwise direction, thereby moving the links 104, 108 toward the left and away from the notch in the collar 98 and permitting the work support 82 to be returned to its original work receiving position. A spring pressed plunger 140 (Fig. 1) is slidably mounted in a hole formed in the lower end of the bracket 96. The plunger 140 is normally urged outwardly by a spring 142 and is arranged to engage the link 104 to prevent the link 104 from striking the bracket 96 when the link is returned

to the position shown in Fig. 1. The plunger 140 thus acts as a yielding stop for the link 104.

After the awls 36 have formed fastening receiving holes in the work and have been returned to their original positions, a staple is driven into the holes. Although fibre staples have good holding power, it is advisable under some conditions to turn or to deflect the legs of the staples in order to insure that the staples will not be pulled out of the work. When fibre staples are bent or deflected, the twists in the paper material from which the staples are formed are displaced relatively to each other and the bent or deflected portions of the staples tend to take a permanent set and to remain in bent or deflected position. This tendency is further increased by the fact that the glue with which the staples are coated softens slightly because of the friction set up between the staples and the work during the driving operation, thereby permitting the twists in the paper material to be more readily displaced. The glue hardens again after the staples have been deflected which tends further to maintain the staple legs in their bent or deflected position. As shown best in Fig. 8, the rear portion of the work support 82 is provided with an arcuate slot 146 in which is mounted a pair of clenching fingers 148. The clenching fingers 148 are formed on the end of a bell crank lever 149 which is pivotally mounted on a shaft 150 supported in suitable bearings formed in an upwardly extending bracket 152 which is formed at the rear end of the block 91. By adjusting the support 82 on the block 91, the slot 146 is positioned properly relatively to the shaft 150. The slot 146 may then be positioned relatively to the driver 18 and the awls 36 by moving the block 91 either forwardly or rearwardly on the end of the work supporting post 90. The fingers 148 are arranged to be moved toward and away from a work piece by 40 connections which will now be described. Referring now to Fig. 3, it will be noted that the lever 149 on the end of which the fingers 148 are formed is pivotally connected to a link 154 by a pin 156. The other end of the link 154 is pivotally connected to a clamping collar 158 which is secured to a sliding rod 160 by means of a clamping screw 162. A block 164 is pivotally secured to the rod 160 by a set screw 166. The block 164 is slidably mounted in a slot formed in the 50 lower end of a lever 168 which is fulcrumed to the head of the machine by a pin 170. The upper end of the lever 168 is provided with a cam roll 172 which engages a cam surface formed on the rear of the cam member 135. When the machine is 55 placed in operation and after a staple has been driven, the high part 174 of the cam 135 engages the cam roll 172 and moves the lever 168 in a clockwise direction, thus causing the fingers 148 to be moved toward the work. When the ends of the fingers 148 engage the ends of the staple legs, they are deflected away from each other and against the surface of the work, as shown, for example, in Fig. 9. The ends of the fingers 148 first engage the staple legs and turn or deflect 65 them against the surface of the work. The fingers 148 then engage the work between the staple legs, as shown in Fig. 9, and compress the work. This compresses the sole member 79 and forces the sole member against the staple legs with the result that the staple is held more firmly in the work. In other words, the holding power of the staple is increased first by turning or deflecting the staple legs and, second, by forcing the portion of the work which is between the 75

staple legs against the staple legs thereby increasing the friction between the staple legs and the sole member 79. When the clenching or deflecting operation has been completed, the high 5 part 174 of the cam 135 passes from beneath the cam roll 172 and the parts are returned to the position shown in Fig. 3 by a torsion spring 178.

The present machine is provided with means for feeding fibre fastening material 180 (Fig. 4) 10 from a roll 182 to the fastening severing and forming instrumentalities of the machine in the manner disclosed in above-mentioned Letters Patent of the United States No. 1,388,846. The feed wheel 184 is operated by lever connections 15 to a cam 186 to feed the fibre fastening material the required distance through a guiding passage formed in a block 188 and through a slot 190 formed in the end of an inside former 192 (Fig. 2). At this time, the inside former 192 is in its 20 forward position to which it has been moved by an arm 194 connected by suitable means to a cam 196. A length of fastening material is then severed from the continuous strip 180 by a severing mechanism of the type disclosed in the Letters Patent mentioned just above. The machine 25 is provided with outside formers (not shown) which are operated to form a staple about the inside former 192. The outside formers are moved downwardly after the fastening material 30 has been severed. After the staple has been completely formed, the inside former is moved rearwardly out of the path of movement of the driver 18, as is usual in machines of this type.

As previously stated, the driver bar 16 is moved 35 toward the work by a spring operated arm 20 which is pivotally mounted in a bracket 24 mounted in the head of the machine. The driver bar 16 is provided with a laterally extending projection 208 which is arranged to engage a cam surface 210 formed on the cam member carried by the main cam shaft of the machine. When the cam member 212 is rotated, the driver bar is moved upwardly until the high part of the cam surface 210 passes from beneath the projection 40 208. The driver bar 16 is then forced downwardly under the influence of the spring 20, forcing the staple through the passage 44 formed in the throat 42 and into holes formed in the work piece by the awls 36.

The parts of the machine have been described 50 in detail but it is believed to be desirable for a better understanding of the invention to describe briefly the operation of the machine. The present invention is illustrated as embodied in a machine particularly adapted for securing sole members to the uppers of stitchdown shoes. The upper of an assembled stitchdown shoe is tensioned by means of a pair of bench pincers and the upper held under tension by the operator while the 55 shoe is placed in position under the throat or abutment 42. After the shoe has been properly positioned relatively to the throat the treadle 84 of the machine is depressed thereby raising the support 82 and clamping the shoe between the throat 42 and the support 82. The treadle 92 is then depressed which causes the clutch of the machine to be engaged to start the machine into 60 operation by power. The links 104, 108 are straightened and the upper end of the link 108 65 engages the notch 99 in the collar 98 thereby causing the support 82 to clamp the shoe firmly against the throat 42. The support 82 is held in clamping position by the links 104, 108 during the hole forming and fastening inserting operations and during the staple clenching operation. 70

At the beginning of the cycle of operation fibre fastening material 180 is fed forwardly, severed, and formed into a staple. Before the fastening forming operation has been completed the awls 36 are thrust downwardly into the work to form 5 holes to receive the legs of the staple and are then returned to their initial position. After the staple is formed it is forced downwardly through the throat of the machine by the driver 18 which is urged downwardly under the tension of the 10 spring 20. The driver 18 is held against the bar of the driven staple while the fingers 148 of the clenching device are thrust against the legs of the staple to bend them against the surface of the work. In order to insure that the legs of the 15 staple will be guided into the holes formed by the awls 36 a finger 220 projects into the path of movement of the driver. The finger 220 is of a width equal to the distance between the legs of the staple and, accordingly, the legs of the staple 20 are supported on all sides during the driving operation. The finger 220 is pivotally mounted and normally urged into the passage 44 of the throat 42 by means of a spring 222. After the staple legs have been bent or deflected the parts of the 25 machine are returned to their initial positions and the machine is then in readiness to perform another cycle of operations.

Having thus described my invention, what I claim as new and desire to secure by Letters 30 Patent of the United States is:

1. In a staple inserting machine, means for inserting staples through a work piece, and means constructed and arranged to engage the projecting ends of the legs of the staples to turn the 35 ends of the legs toward the surface of the work after the staples have been completely inserted in the work and forcibly to engage the work between the legs of the staples thereby compressing the work and increasing the holding power of the 40 staples.

2. In a staple inserting machine, means for forming staple receiving holes in a work piece, means for driving staples through said holes, and means for bending the projecting ends of the legs 45 of said staples away from each other and toward the surface of the work after the operation of the staple driving means has been completed and to compress the work between the staple legs to close the staple receiving holes about the legs of the 50 staples to increase the holding power of the staples.

3. In a machine for inserting staples, means for forming holes in a work piece, means for driving staples through said holes, a work support, and means associated with said work support constructed and arranged to compress the work between the staple legs and to bend the projecting 55 ends of the legs away from each other against the surface of the work after the staples have been completely inserted in the work.

4. In a machine for inserting staples, awls for forming holes in a work piece, a driver for inserting staples in said holes, means for moving the driver toward the work to insert a staple and to hold the driver against the staple after the staple has been inserted, and a clenching member constructed and arranged to compress the portion of the work between the legs of the staple and to bend the ends of the legs in opposite directions 65 away from the bar of the staple and against the surface of the work after the staple has been inserted and while the driver is held against the staple.

5. In a machine for inserting staples, a pair of 75

awl arranged to form pairs of holes in a work piece, a driver, means for forming staples from a length of fastening material, means for moving said driver toward the work to insert a staple in said holes and to hold the driver against the bar of the staple after the staple has been inserted in the work, a work support, and a clenching member associated with said work support constructed and arranged to engage the work to compress the work between the legs of the staple and to bend the legs away from each other and against the surface of the work after the staple has been inserted in the work and while the driver is held against the staple.

15 6. In a machine for inserting staples, awls arranged to form pairs of holes in a work piece, a driver, means for moving the driver toward the work to insert a staple in said holes and to hold the driver against the staple after the staple has been inserted in the work, a work support having a passage therein, and means movable in said passage arranged to move to bend the legs of the staple away from each other and against the surface of the work and to compress the portion 20 of the work between the staple legs after the staple has been inserted and while the driver is held against the staple.

7. In a staple inserting machine, an abutment having a staple guiding passage, a work support arranged for movement toward said abutment to clamp a work piece against the abutment, means for forming holes in a work piece for receiving the legs of staples, means for inserting staples in said holes, and means arranged for movement to turn the legs of the staples toward the surface of the work piece after the staples have been driven and to engage the work between the legs of the staples thereby compressing the work and forcing the work against the legs of the 40 staples.

8. In a staple inserting machine, means for inserting staples in a work piece, a throat having a passage through which the staples are driven, a work support constructed and arranged to clamp the work against the throat during the staple inserting operation, and means associated with said work support constructed and arranged to engage the ends of the legs of the staples to turn the legs toward the surface of the work and 45 to compress the work between the legs of the staples after the staple inserting operation has been completed.

9. A machine for inserting staples having, in combination, means for forming staples, a pair 50 of awls constructed and arranged to form pairs of staple receiving holes in a work piece, a driver for inserting staples in said holes, a work support arranged to clamp the work during the hole forming and staple inserting operations, and means associated with said support constructed and arranged to engage the ends of the legs of the inserted staples to turn the ends of the legs toward the work and to compress the portion of the work between the legs of the 55 staples thereby decreasing the effective diameter of the holes and increasing the holding power of the staples.

10. In a staple inserting machine, a driver, a work support arranged to clamp the work during the staple inserting operation, and a pair 60 of fingers constructed and arranged to engage the ends of the legs of the staples after the staples have been inserted in the work to turn the ends of the legs of the staples toward the surface of the work, said fingers being arranged also to

engage the work between the staple legs to force the work against the staple legs thereby increasing the holding power of the staples.

11. In a staple inserting machine, means for forming staples from a length of fastening material, a pair of awls constructed and arranged to form pairs of staple receiving holes in a work piece, a driver for inserting staples in said holes, a work support arranged to clamp the work during the hole forming and staple inserting operations, and a pair of fingers mounted in said support and constructed and arranged to engage the ends of the staple legs after the staple inserting operation has been completed to turn said ends toward the work and to force the portion of the work between the legs of the staples against the legs thereby increasing the holding power of the staples.

12. A staple inserting machine having, in combination, a pair of awls constructed and arranged to form staple receiving holes in a work piece, a driver, means for operating said driver to insert staples in said holes, a stationary abutment having a passage through which the staples are driven, a work support arranged to clamp the work against the abutment during the hole forming and staple inserting operations, a pair of fingers associated with said work support, and means constructed and arranged to move said fingers toward the work after the staple inserting operation has been completed to engage the projecting ends of the legs of the inserted staples to turn the ends of the legs toward the surface of the work and to compress the portion of the work between the legs of the staples thereby increasing the holding power of the staples.

13. In a staple inserting machine, means for inserting staples in the work piece, a throat having a passage through which staples are driven, a work support constructed and arranged to clamp the work against the throat during the staple inserting operation, a pair of fingers mounted in said work support, and cam operated means for moving said fingers toward the work after the staple inserting operation has been completed to turn the ends of the legs of the staples toward the surface of the work and to compress the portion of the work between the staple legs thereby forcing the work against the staple legs and increasing the holding power of the staples.

14. In a machine for inserting staples, means for forming holes for the reception of the legs of staples, means for inserting staples in said holes, a throat having a passage for said inserting means and a passage for said hole forming means, said passages being arranged at an angle to each other and intersecting each other at the lower end of the throat, and means constructed and arranged to engage the projecting ends of the staple legs to turn the ends of the legs toward the surface of the work.

15. In a machine for inserting staples, awls for forming holes in a work piece for the reception of the legs of staples, a driver for inserting staples in said holes, a throat having a driver passage 65 and a passage for each of said awls, said passages being arranged at an angle to each other and intersecting each other at the lower end of said throat, and means constructed and arranged to engage the projecting ends of the staple legs 70 after the staples have been completely inserted in the work to turn the ends of the legs toward the surface of the work.

16. In a machine for inserting staples, awls for forming holes in a work piece for the recep- 75

- tion of the legs of staples, a driver for inserting staples in said holes, a throat having a driver passage and a passage for each of said awls, said driver and awl passages being arranged at an angle to each other and intersecting each other at the lower end of said throat, a work support having a passage therein, and means movable in said passage arranged to bend the legs of the staples against the surface of the work after the staples have been inserted and while the driver is held against the staples.
17. In a machine for inserting staples, awls for forming holes in a work piece for the reception of the legs of staples, a driver for inserting staples in said holes, a throat having a driver passage and a passage for each of said awls, said driver and awl passages being arranged at an angle to each other and intersecting each other at the lower end of said throat, a work support arranged for movement toward said throat to clamp a work piece against said throat, and means arranged for movement to turn the legs of the staples toward the surface of the work piece after the staples have been driven.
18. In a machine for inserting staples, awls for forming holes in a work piece for the reception of the legs of staples, a driver for inserting staples in said holes, a throat having a driver passage and a passage for each of said awls, said driver and awl passages being arranged at an angle to each other and intersecting each other at the lower end of said throat, a work support arranged to clamp the work against the throat during the hole forming and staple inserting operations, a pair of fingers associated with said work support, and means constructed and arranged to move said fingers toward the work to engage the projecting ends of the legs of the inserted staples to turn the ends of the legs toward the surface of the work after the staple inserting operation has been completed.
19. In a machine for inserting fastenings, fastening inserting mechanism, a work support movable from a work receiving position to a work clamping position, manually operated means arranged to move the support toward work clamping position, a projection on the work support, a toggle having a link constructed and arranged to engage the projection after the support has been moved manually toward work clamping position, and power operated means for straightening the toggle to apply clamping pressure to the work.
20. In a machine for inserting fastenings, fastening inserting mechanism, a work support movable from work receiving position to work clamping position, manually operated means constructed and arranged to move the work support to work clamping position, a member secured to the work support, a toggle having a link arranged to engage said member only after the work support has been moved toward clamping position by the manually operated means, and power operated means arranged to straighten the toggle to move the support to apply a predetermined clamping pressure to the work prior to the fastening inserting operation.
21. In a machine for inserting staples, means for inserting staples in a work piece, a throat through which the staples are driven into the work, a work support arranged to clamp the work against said throat to prevent displacement of the work during the staple inserting operation, manually operated means for moving the work support toward work clamping position, a mem-
- ber secured to said support, a pair of links forming a toggle, one of said links being pivoted to the frame of the machine and the other link being arranged to engage the member secured to the support after the support has been moved toward work clamping position, and power operated means constructed and arranged to straighten said toggle to move the support to apply a predetermined clamping pressure to the work.
22. In a machine for inserting staples, means for forming holes in a work piece to receive the legs of the staples, means for inserting staples in said holes, a throat through which the staples are driven, a work support arranged to clamp the work piece against said throat to prevent displacement of the work during the hole forming and staple inserting operations, manually operated means for moving the support toward work clamping position, a member secured to said support, a link pivotally secured to the frame of the machine, a second link secured to the other end of said first-mentioned link, said second-mentioned link being so arranged that engagement of said second-mentioned link with the member secured to said support is prevented until the work support has been moved manually a predetermined distance toward said support, and power operated means for operating said links to apply a clamping pressure to the work.
23. In a machine for forming and inserting fibre staples, means for forming fibre staples from a length of fibre fastening material, a pair of awls for forming a pair of holes for the reception of the legs of fibre staples, a driver for inserting the fibre staples in said holes, a throat having passages arranged at an angle to each other in which the awls and the driver are reciprocated, and a work support constructed and arranged to clamp the work against the throat during the hole forming and staple driving operations.
24. In a machine for forming and inserting fibre staples, means for severing fibre fastening material, means for feeding the fibre fastening material to the severing means, means for forming a fibre staple from said length of fastening material, awls for forming holes in the work to receive the legs of said fibre staple, a driver for inserting the staple in said holes, a throat through which the staple is driven, a work support arranged to clamp the work against the throat during the hole forming and staple inserting operations, and means associated with said work support movable to compress the portion of the work between the legs of the staple to force the work about the staple legs and to engage the projecting ends of the staple legs after the staple has been driven to turn the staple legs against the surface of the work.
25. In a machine for forming and inserting fibre staples, means for forming fibre staples from a length of fibre fastening material, awls for forming a pair of holes in the work to receive the legs of a fibre staple, a driver for inserting the legs of the fibre staple in said holes, a throat having awl and driver passages intersecting each other at the lower end of the throat, a work support arranged to clamp the work against the lower end of the throat during the hole forming and staple inserting operations, and a pair of fingers associated with said support arranged to engage the projecting ends of the staple legs after the fibre staple has been completely inserted in the work to turn the ends of the legs against the surface of the work.
